UNITED STATES PATENT OFFICE.

LEON W. BOSSERT, OF UTICA, NEW YORK.

SECTIONAL GANG-BOX FOR PUSH-BUTTON SWITCHES.

No. 859,363.

Specification of Letters Patent.

Patented July 9, 1907.

Application filed February 19, 1906. Serial No. 801,830.

To all whom it may concern:

Be it known that I, LEON W. BOSSERT, a citizen of the United States, residing at Utica, in the county of Oneida and State of New York, have invented a certain 5 new and useful Improvement in Sectional Gang-Boxes for Push-Button Switches; and do hereby declare the following to be a full, clear, and exact description of the invention, such as will enable others skilled in the art to which it appertains to make and use the same, 10 reference being had to the accompanying drawings, and to the letters and figures of reference marked thereon, which form a part of this specification.

This invention relates to new and useful improvements in multi-sectional gang boxes for rotary or push-15 button switches, and provides means whereby sections, preferably drawn up from metal, may be assembled together to accommodate varying numbers of switches.

Heretofore it has been the common practice to construct an expensive wood or metallic model for the 20 box and have castings made from such models and it frequently happens that such castings are unsatisfactory, especially where a large number of switches are to be housed in one box, and in a commercial way, boxes made in this manner are almost prohibitive 25 owing to the cost of construction. A further objection to the castings made from the models referred to is that the boxes are warped owing to unequal shrinkage of the iron of which they are composed.

By the construction of box made in accordance with 30 my invention, in which the interchangeable sections are utilized, a box of any desired length to accommodate any number of switches is afforded which are usually necessary in office buildings, the sections of which gang box may be securely held together and 35 provided with a single or sectional cover as may be desired.

My invention is illustrated in the accompanying drawings, which, with the letters of reference marked thereon, form a part of this application, and in which:— 40 Figure 1 is a top plan view of a two-gang box. Fig. 2 is a sectional view on line 2—2 of Fig. 1. Fig. 3 is a perspective view showing the two sections of the box illustrated in Fig. 2, disassembled. Fig. 4 is a perspective view of a cover to the two-gang box. Fig. 5 is a top plan view of a three-gang box with cover fastened thereto, and Fig. 6 is a side elevation of a three-gang box.

Reference now being had to the details of the drawings by letter, A and A' designate the two sections of 50 a two-gang box, which sections have inwardly turned flanges C at their upper edges, each of which has indentures D at intervals with apertures D' in each indenture for the reception of the screws E which pass through apertures in the cover F, thereby forming a 55 secure means for holding the cover to the sections of a box.

Referring to Figs. 2 and 3 of the drawings, it will be noted that the meeting end of the section A of the box has an outwardly spread portion H adapted to receive the adjacent end K of the section A'. An aperture H' is formed in the bottom of the spread portion H and is adapted to receive a lug K' projecting from the bottom of the section A' adjacent to its meeting end. When the two sections are adjusted together in the manner shown in Fig. 2 of the drawings, 60 the flange at the meeting end of the section A' will enter the recesses a formed in the adjacent end of the flanges upon the section A, and the two flanges will be in alinement. The cover shown in Figs. 1 and 4 of the drawings is provided with a flange F' about the 65 central opening therein, and said flange has recesses N therein at positions opposite, as shown clearly in Figs. 1 and 4, and the bottom of each recess has a threaded aperture to receive a screw O to which the switch is adapted to be attached. The ends of the 70 cover are provided with elongated curved slots Q adjacent to the longitudinal center of the box and are provided to allow the box to be adjusted in perfect alinement.

While I have shown the cover as being made of a 75 single piece, it will be understood that the same may be composed of two or more sections, if desired, although I have found that boxes made up of series of sections and held together by the overlapping meeting ends in the manner shown and described, will be more 80 rigidly held together by the provision of a cover of a single piece of metal which may be reinforced by extra screws, if desired, in the manner shown in the drawings.

In Figs. 5 and 6 of the drawings, I have shown the 85 box as adapted for a gang of three switches in which a central interchangeable section is provided. It will be noted that by the provision of the intermediate interchangeable sections, a box may be built up of any desired length to accommodate a large number of 90 switches which may be used in one box either in single, double, triple or quadruple rows, the sections being provided preferably with temporary plugged outlets 95 which may be readily removed by a sharp blow of a hammer or other tool when it is desired to pass a conduit through one of the sections.

From the foregoing, it will be noted that a sectional gang box for rotary or push-button switches is provided having interchangeable sections and affording means whereby boxes of varying lengths may be built 100 up to meet different requirements.

What I claim is:—

1. A gang box adapted for use for rotary or push-button switches, comprising a plurality of sections, the tops of which are open and each section having a continuous inwardly turned flange, one of said sections having an outwardly flaring angled flange about its bottom and sides adapted to receive the inner end of the other section, with 110

the upper surfaces of the bottoms of the box flush, apertured indentures formed in the flanges about the upper marginal edges of the sections, and a closure adapted to be fastened to the flanges of the sections, whereby the same 5 may be held together, as set forth.

2. A gang box adapted for use for rotary or push-button switches, comprising a plurality of sections, the tops of which are open and each section having a continuous inwardly turned flange, one of said sections having an outwardly flaring angled flange about its bottom and sides 10 adapted to receive the inner end of the other section, with the upper surfaces of the bottoms of the box flush, apertured

indentures formed in the flanges about the upper marginal edges of the sections, a lug projecting from the bottom of one of the sections and adapted to engage an aperture in the flange upon the bottom of the other section, and a closure designed to be fastened to said continuous flanges of the sections, as set forth. 15

In testimony whereof I hereunto affix my signature in the presence of two witnesses.

LEON W. BOSSERT.
